UNITED STATES PATENT OFFICE.

DE WITT LOOMIS, OF DETROIT, MICHIGAN.

DRAFT-RIGGING.

SPECIFICATION forming part of Letters Patent No. 613,522, dated November 1, 1898.

Application filed June 29, 1898. Serial No. 684,753. (No model.)

To all whom it may concern:

Be it known that I, DE WITT LOOMIS, of Detroit, in the county of Wayne and State of Michigan, have invented certain new and useful Improvements in Draft - Rigging; and I hereby declare that the following is a full, clear, and exact description thereof, reference being had to the accompanying drawings, which form part of this specification.

10 This invention is an improvement in draft-rigging for railway-cars; and the object of my invention is to provide a double or tandem draft-rigging of simple construction and having few parts, so that any broken part
15 can be easily replaced and which can be easily and cheaply substituted for the forms of draft-rigging now in use by most railroads, as many of the parts of my rigging are like those usually found in the draft-rigging now
20 in common use.

20 in common use.
The invention therefore consists in the
novel construction and combination of parts
hereinafter described and claimed, and illus-
trated in the accompanying drawings, which
25 form part of this specification, and similar
letters of reference thereon represent similar
parts throughout the figures.

Figure 1 is a side view, partly sectional, of a draft-rigging embodying my invention. Fig. 2 is a cross-section on line 2-2, Fig. 1. Fig. 3 is a plan view of Fig. 1, and Fig. 4 is a sectional view of a modification thereof.

35 a sectional view of a modification thereof.
A A, Fig. 1, are the draw-bar timbers, to which are attached the side plates or follower-guides B B, made of iron and firmly secured to the timbers A by bolts *b*. The guide-plates B are set into recesses in the timbers A, as shown, but are provided with flanges B' at each end, which serve to prevent the timbers 40 A A from breaking out at the points where the guide-plates are let in them. The guide-plates are also provided with vertical stops C c C' C² c² C³ c³, as shown, and to the lower edge of each guide-plate is attached a bar B³ 45 by bolts *b*³, upon which bar the followers D D' D² D³, hereinafter described, rest.

The follower D is placed between stops C c and limited in its movements thereby. Follower D' is placed between stops C' C', follower D² between stops C² c², and follower D³ between stops C³ c³.

A yoke or strap E is solidly and firmly fixed to the end of the draw-bar F by the bolts f or in other convenient manner, and said yoke can be made of one piece, as shown in the 55 drawings, or in other desired manner, its exact construction not being essential. This yoke extends between the guide-plates B B and surrounds all the followers D D' D² D³, resting upon bars B³, said followers being held in their normal position respectively against the stops C C' C² C³ by the pressure of coil-springs H h and H' h', interposed between the followers, as shown. 60

Supported in central guide-openings in the 65
followers D D' is a short rod g , which trans-
fixes and suspends the springs H h, as shown,
and supported in openings in the followers
D² D³ is a similar rod g' , which transfixes and
suspends the springs H' h'. Interposed be-
tween the followers D' D² and between the
ends of the rods g g' is a plate g², loosely hung
upon and guided by the yoke E, as shown.
The springs H h and H' h' may be of any
desired construction, and, as shown, springs
h h' are smaller than and arranged inside of
springs H H', respectively. It will be noted
that the rods g g' are not directly attached in
any way to either the draw-bar F or the yoke,
but are supported by the followers and rest
loosely in the guide-holes therein. 70 75 80

In coupling cars or "buffing" the end of the draw-bar F will first strike against the follower D, thereby compressing the outermost springs H h against the follower D', 85 which is held by stops C'. At the same time it can push the rod g against plate g^2 , which contacts with follower D ^{2} and causes it to compress springs H' h' against follower D ^{3} , which is held by the stop C ^{3} . In the pulling 90 strain the action would be reversed. The inner end of the yoke E would strike against follower D ^{3} and compress the springs H' h' against the follower D ^{2} , held by stop C ^{2} . At the same time the rod g' is pushed forward 95 against plate g^2 , which presses against follower D' and compresses springs H h against the follower D, which is held in position by the stop C.

By shortening the rod g the springs $H\ h$ 100 could be compressed upon the buffering strain before the springs $H' h'$ were compressed,

and by shortening rods g' springs $H' h'$ could be compressed on the pulling strain before springs $H h$.

It will be seen that by this construction the 5 parts can be very readily arranged so as to successively or simultaneously compress the sets of springs, as may be desired.

In Fig. 4 I have omitted the plate g^2 and the rod g' , and the followers $D D^2 D^3$ may be left 10 imperforate, the pin g still passing through the follower D' . In this construction on the draft strain springs $H H'$ will be compressed, but on the buffing strain both sets of springs will be compressed, as rod g will strike the 15 follower D^2 and cause it to compress the springs $H' h'$ along with the springs $H h$. It is obvious that the same effect would be realized if the rod g passed through the follower D and struck again the end of the draw-bar.

20 Having thus described my invention, what I therefore claim as new, and desire to secure by Letters Patent thereon, is—

1. In a draft-rigging, the combination of the draw-bar, the guide-plates, the four followers supported thereon limited in their movements by stops on said guide-plates and the springs interposed between the first and second, and third and fourth followers, and a rod or pin passing through a set of springs 30 and through an inner follower, and the yoke attached to the draw-bar and surrounding the followers, springs and rod, for the purpose and substantially as described.

2. In a draft-rigging for cars, the combination of the opposite guide-plates, the followers mounted thereon, springs interposed between the first and second and third and fourth followers, the movable piece inter-

posed between the second and third followers, and a rod supported by said followers 40 contacting said piece; with the draw-bar and yoke attached thereto, surrounding the followers, springs and rods, for the purpose and substantially as described.

3. In a draft-rigging for cars, the combination of the opposite guide-plates, the four followers mounted thereon, and limited in their movements by stops on said guide-plates; springs interposed between the first and second, and third and fourth followers, 50 the pair of rods supported by said followers respectively transfixing the springs; with the draw-bar and yoke attached thereto, surrounding the followers and springs for the purpose and substantially as described. 55

4. In a draft-rigging for cars, the combination of the opposite guide-plates, the four followers mounted thereon, and limited in their movements by stops on said guide-plates; springs interposed between the first and second, and third and fourth followers, the pair of rods supported by said followers respectively transfixing the springs and the movable piece interposed between the inner ends of said rods; with the draw-bar and yoke attached thereto, surrounding the followers, springs and rods, for the purpose and substantially as described. 60

In testimony that I claim the foregoing as my own I affix my signature in presence of 70 two witnesses.

DE WITT LOOMIS.

In presence of—

HARRY C. BULKLEY,
ALEXANDER HAMILTON SIBLEY.
